Patented December 13, 1904.

UNITED STATES PATENT OFFICE.

EMILY INEZ DENNY, OF SEATTLE, WASHINGTON.

DESIGN FOR AN ARABESQUE PATTERN.

SPECIFICATION forming part of Design No. 37,264, dated December 13, 1904.

Application filed May 24, 1904. Serial No. 209,596. Term of patent 7 years.

To all whom it may concern:

Be it known that I, EMILY INEZ DENNY, a citizen of the United States, residing at Seattle, in the county of King and State of Washington, have invented a new, original, and ornamental Design for an Arabesque Pattern, of which the following is a specification, reference being had to the accompanying drawing, forming part thereof.

○ The figure of the drawing is an elevation

view of my new ornamental design for an arabesque pattern.

What I claim as new, and desire to secure by Letters Patent, is—

The ornamental design for an arabesque pattern as shown.

EMILY INEZ DENNY.
